UNITED STATES PATENT OFFICE

171,064

RUG

Albert T. Taraborelli, Providence, R. I.

Application June 6, 1952, Serial No. 20,063

Term of patent 14 years

(Cl. D92—21)

To all whom it may concern:

Be it known that I, Albert T. Taraborelli, a citizen of the United States, residing at Providence, in the county of Providence and State of Rhode Island, have invented a new, original, and ornamental Design for a Rug, of which the following is a specification, reference being had to the accompanying drawing, forming part thereof.

The figure is a plan view of a rug, showing my new design.

I claim:

The ornamental design for a rug, as shown.

ALBERT T. TARABORELLI.
